UNITED STATES PATENT OFFICE.

JOHN F. LARKIN, OF HARTFORD, CONNECTICUT.

TOWEL BINDER.

Application filed November 18, 1921. Serial No. 516,199.

To all whom it may concern:

Be it known that I, JOHN F. LARKIN, a citizen of the United States, residing at Hartford, in the county of Hartford and 5 State of Connecticut, have invented a new and useful Improvement in Towel Binders, of which the following is a specification.

In hotels, restaurants and other public places it is common to have individual towels 10 on racks, rods, hooks, or chains so arranged and locked that the towels may be used for proper purposes but cannot be stolen or carried away by unauthorized persons. Towels for such use when clean are commonly tied 15 up at the laundry in bundles of fifty with the holes in the towels in line so that they may be readily threaded on the pin, hook or chain of the anti-theft device where they are placed for use.

20 This invention relates to a device which is designed to be applied to the towels at the laundry for retaining them in a desirable and convenient condition and arrangement while being transported to the place of use 25 and transferred to the anti-theft device.

The object of the invention is to provide a very simple and cheap device by means of which the towels can be easily bundled together at the laundry and be securely held 30 during handling and transportation in such shape and relation that they can be transferred without loss of time directly from the binder to the anti-theft device.

In the accompanying drawings Figure 1 35 shows a plan of a device which embodies this invention, unfolded and in position to receive towels. Fig. 2 shows a side view of the device unfolded. Fig. 3 shows a perspective view of the binder holding a bundle of 40 towels. Fig. 4 is an elevation showing the manner of fastening the binder strips when holding a bundle of towels.

The device shown has rigid or semi-rigid 45 end pieces 1 and 2. These end pieces may be made of strips of wood or metal and they are desirably covered with canvas or other textile material. The end strips are connected by flexible bands 3 which may be made of tape, canvas or other suitable material. Attached to the strip 1 between the bands is a fastening tab 4. This tab is desirably made of elastic webbing a little shorter than the thickness of the bundle of towels to be held and it has a perforation 55 protected by a grommet 5 at its free end. The end strip 2 has a grommet protected

perforation 6 and the end strip 1 has a perforation protected by a grommet 7.

A pin 8 of wood or other suitable material is loosely fitted in the hole through the 60 strip 1. This pin desirably has heads 9 and 10 which are slightly larger than the hole so that the pin cannot drop out.

In the laundry or other place where the towels are packed, the clean towels are laid 65 upon the binder with the usual openings through them threaded upon the pin. When the required number of towels have been thus piled on the binder the end strip 2 is brought around the towels and its opening 70 6 thrust over the head of the pin. The end strips are pressed together and then the elastic fastening tab is brought around the end of the bundle and its perforation thrust upon the pin. This fastening tab being elas- 75 tic draws the end strips 1 and 2 together so that with the bands the towels are tightly bound together. When the towels are bundled in this manner they are usually thrown into the delivery wagon and carried to the 80 place of use where the attendant opens up the anti-theft device, disconnects the fastening tab of the binder from the pin and then disengages the strip 2 and threads the towels upon the pin, hook or chain of the 85 anti-theft device without dislocating them, the anti-theft holding part following the pin 8 down through the openings in the towels as they are placed in position. With this simple construction towels can be quickly 90 bound in packages and securely held in desired formation during transportation and without loss of time transferred to the anti-theft device.

The invention claimed is:

1. Means for binding towels comprising a pair of perforated end strips, flexible bands connecting the strips, a pin arranged to fit the perforations in the strips, and fastening means for preventing the strips from separating when on the pin with a package of towels between.

2. Means for binding towels comprising a pair of rigid strips, one of said strips having a perforation through which a pin 105 loosely extends and the other of said strips having a perforation adapted to fit upon the pin, flexible bands connecting the strips, and means for holding the strips from separating when the pin is threaded through the 110 strips and through towels located between the strips.

3. Means for binding towels comprising a pair of perforated strips, flexible bands connecting the strips, a pin arranged to fit the perforations in the strips, and fastening means attached to one of the strips and adapted to engage the pin over the other strip for holding the strips from moving apart when in use.

4. Means for binding towels comprising a pair of perforated strips, flexible bands connecting the strips, a pin fitting the perforations in the strips, and an elastic strip fastened to one of the rigid strips and adapted to engage with the pin over the other strip.

5. Means for binding towels comprising a rigid strip having a pin projecting at right

angles from its center, a rigid strip having a perforation adapted to fit the pin, flexible bands connecting the strips, and an elastic strip fastened to one of said rigid strips and adapted to engage with the pin over the other strip.

6. Means for binding towels comprising rigid strips having central perforations, flexible bands connecting the strips, a rigid pin adapted to fit the perforations in the strips, and an elastic strip arranged to engage with the pin outside of the strips for holding the strips together with a package of towels between.

JOHN F. LARKIN.
